APPARATUS FOR PREVENTING CONDENSATION IN GAS MAINS

Karl Koller, Budapest, Hungary

Application June 30, 1937, Serial No. 151,255

2 Claims. (Cl. 48—190)

This invention relates to the distribution of combustible gas containing condensable materials, particularly producer gas made in a producer employing bituminous coal as the fuel.

In many plants, combustible gas containing tarry matter including tar acids and other condensable constituents, e. g., producer gas generated by blowing air through a bituminous coal fuel bed, is cleaned by passage through one or more washing and grid chambers or other cleaning equipment and the resultant cleaned gas distributed through a piping system to furnaces or other appliances where it is burned. In such plants, reduction of the temperature of the gas between the cleaning equipment and the point of consumption causes condensation of condensable constituents such as tarry matter in the lines leading to the burners, requiring frequent interruption of plant operations to clean the gas distribution conduits, meters, etc. Such interruptions, it will be appreciated, result in loss of time and labor in cleaning the distribution system and result in the formation of objectionable, dense clouds of smoke when the deposits of condensed material are burned to effect their removal. Moreover, in many plants where producer and other combustible gas is employed, the washing or scrubbing liquor from the gas washers contains tar acids, including phenols, and, therefore, cannot be discharged into streams. In many localities municipal ordinances prohibit the discharge of such waste liquors into streams and waterways. Hence, such waste liquors or effluent present a difficult disposal problem.

It is an object of this invention to feed or dis-

tribute combustible gas containing condensable constituents such as producer gas made from bituminous coal in such manner that condensa-

tion of tarry material in the gas line is minimized

or substantially completely eliminated.

It is a further object to distribute combustible gas such as producer gas as generated and without subjecting the same to water washing through the usual distribution systems in industrial plants

so as to avoid objectionable deposits in such systems.

Other objects and advantages of the invention will appear from the following description:

In accordance with the invention, I introduce into the distribution system hot gases at a temperature and in amount such that the combustible gas reaches the gas consuming appliances at a temperature above the dew point of the condensable materials therein. Preferably the combustible gas is superheated to a temperature such

that it reaches the appliances at a temperature equal to or above the temperature of the gas entering the mains by burning a portion of the gas and conducting the hot products of combustion into the distribution system where it mixes with the combustible gas. Thus heat losses from the system as the gas flows therethrough are compensated by the hot gases added to the system, thereby preventing cooling of the gas to a point where substantial condensation of the condensable materials will occur. Accordingly, in plants where the waste liquors present the hereinabove mentioned disposal problem, water washing of the gas may be eliminated and condensation of tarry and other condensable constituents within the distribution system prevented by the practice of this invention.

The invention also comprehends apparatus for preventing condensation of condensable materials in a gas distribution system involving burners having combustion chambers communicating with the system, lines for supplying air to the burners, lines for supplying combustible gas to the burners and mechanism for automatically terminating flow of gas and air to the burners when the gas pressure in the system falls below a predetermined minimum.

A preferred embodiment of the invention is shown for purposes of exemplification in the accompanying drawing, wherein

Fig. 1 is a view, somewhat diagrammatic in character of a gas distribution system equipped in accordance with the invention,

Fig. 2 is a view illustrating on an enlarged scale a portion of the apparatus of Fig. 1, and

Fig. 3 is a sectional view through a gas distribution main equipped in accordance with the invention.

Referring more particularly to the drawing, reference numeral 8 indicates generally apparatus for producing combustible gas which may include a producer containing an incandescent bed of bituminous coal through which air is blown upwardly, the resultant producer gas passing off from the top of the producer through gas offtake 11. As is well known in the art, gas such as producer gas made from bituminous coal contains objectionable impurities and is ordinarily subjected to cleaning operations such as scrubbing in washing and grid chambers which result in partial cleaning of the gas. The effluent liquor from the scrubbers contains tar acids including phenols and hence present a difficult disposal problem.

In the embodiment of the invention shown in

Fig. 1, the gas from the producer is passed not through scrubbers where it would be contacted with water or other liquid, but through a mechanical dust collector such as a cyclone separator 12. From this dust collector the gas is introduced into distribution main 16 equipped with branches 18 and 20 leading to burners 22 and 24 of furnaces 26 and 28 respectively. The burners 22 and 24 are ordinarily located some distance from the dust collector, as indicated by the broken mains connecting line 16 with furnaces 26 and 28, so that the gas is subject to substantial reduction in temperature due to heat losses between the dust collector and the furnaces. In order to avoid condensation of the tarry materials in the distribution mains, particularly the branch mains leading to the burners, thereby clogging the mains, meters, etc. and necessitating frequent shutdowns to clean out the mains, I have equipped the distribution mains for the gas at suitable points with burners, designated generally by reference numerals 30 and 32 in Fig. 1 and shown in detail in Fig. 3.

Each burner includes a valved air inlet 34 connected to an air supply line 35 equipped with a water seal 37 and combustible gas inlet 39 connected to gas supply line 41 equipped with water seal 43, refractory lined combustion chamber 45, electric heating element 47 and perforated flame spreader or distributor 49. The open end 51 of the combustion chamber projects into the gas distribution main, any suitable joint 53 being employed to form a gas tight connection between the main and exterior of the burner. The water seals 37 and 43 prevent back flow of air and gas through the lines supplying 35 and 41 respectively.

Gas supplied to the burners through supply line 41 may be clean gas available at the plant or may be bled off from the distribution system. For the latter purpose line 41 may be connected, e. g., to distribution main 16 at any suitable point.

In Fig. 2 I have illustrated somewhat diagrammatically an automatic mechanism for terminating the flow of air and gas to the burners in event the supply of combustible gas through the distribution main 16 is shut off or the pressure in the system for any reason falls below a predetermined minimum. The cutoff mechanism involves an air valve 60 in each of the air inlet conduits 34 and a gas valve 62 in each of the gas inlet conduits 39 to the burners. The gas and air valves for each burner are joined for simultaneous operation by connection 64 and each pair of valves 60, 62 is equipped with an operating lever 66 connected to cable 68 through branch cables 70; cables 68, 70 run over pulleys 72. Cable 68 is connected at one end to a counter-weight 74 preferably constructed as a piston and sliding in cylinder 76 provided with an adjustable port 78. The piston and cylinder form in effect a dash pot to cushion the fall of the piston counter-weight upon release of the cable 68 in a manner hereinafter described. The other end of cable 68 is wound on drum 80 equipped with ratchet 82 and manually operated handle 84. Detent 86 is rigidly connected at one end to lever 88 and the other end of the 70 detent cooperates with ratchet 82. Lever 88 is pivotally mounted at 90 and equipped at one end with an adjustable weight 92. The other end of the lever is connected to bell 94 partially submerged in a body of liquid in bell tank 96. An extension 98 of gas line 41 terminates in and

discharges gas into the space beneath bell 94 so that the pressure beneath the bell corresponds to the pressure in the gas line and distribution system.

The operation of the device is as follows: 5 When gas is passing through the mains 16, 18 and 20 to burners 22, 24, electric current is supplied to heating element 47 to heat it to incandescence and levers 66 are manually lowered to permit flow of gas and air to the burners 30, 32; 10 the incandescent heating element ignites the mixture of gas and air. The amount of gas and air fed to the burners may be controlled by adjustment of valves 60, 62 and is preferably such that the products of combustion from the 15 burners impart to the gas flowing through the distribution system superheat in amount sufficient to prevent the temperature of the gas from falling below its dew point prior to reaching the burners. Upon drop of pressure in the distribution 20 system, the pressure in line 41 and extension 98 also falls thus causing a drop in pressure beneath the bell 94. Air pressure forces the bell down causing rotation of lever 88 in clockwise direction about its pivot and raising of detent 25 86. When the pressure beneath the bell falls a predetermined amount, detent 86 is disengaged from ratchet 82 permitting weight 74 to unwind cable 68 from drum 80 and close air and gas valves 60, 62 by raising levers 66. When it is 30 desired to again start the burners in operation, cable 68 is wound on drum 80 by turning handle 84, detent 86 engaged with the ratchet 82 and valves 62, 60 set to permit flow of the desired amount of gas and air to the burners. 35

Preferably the burners are located in the gas distribution system at points at which objectionable condensation begins to occur. The location of the burners may be influenced by many factors such as the length of the distribution 40 system, the rate of heat loss from the gas flowing through the system, etc. While I have illustrated in Fig. 3 burners located in the branch distribution mains leading from main 16 to the burners, it will be appreciated that if objectionable 45 condensation occurs in main 16, this main may be equipped with one or more burners at points where condensation begins to occur.

It will be noted this invention provides a process and apparatus for preventing condensation 50 of tarry matter from combustible gases, in gas distribution systems, containing such matter by introducing into the mains at suitable points hot gases in amount and at a temperature sufficient to prevent lowering of the temperature 55 of the gas below its dew point prior to reaching the burners. In accordance with my invention the gas as generated need not be washed and hence waste liquors which would present a difficult disposal problem are not formed; and at 60 the same time objectionable deposits of condensable constituents in the distribution system are avoided.

While I have disclosed a preferred embodiment 65 of the invention, it is to be understood the invention is not to be restricted to the present disclosure otherwise than as defined by the appended claims.

I claim:

1. Apparatus comprising in combination a gas 70 main for conveying combustible gas containing condensable constituents, means for preventing deposition of said constituents in said main comprising a burner for producing hot products of combustion, means for introducing said products 75

of combustion into said main in amount and at a temperature sufficient to prevent the temperature of said combustible gas from falling below its dew point during flow through said main to 5 its destination, means for feeding air to said burner, means for withdrawing a portion of the gas from said main and feeding it to said burner, and means responsive to pressure conditions within said main for preventing flow of 10 air and gas to said burner when the pressure within the main falls below a predetermined minimum.

2. Apparatus comprising in combination gas consuming appliances and a gas distribution system including a gas main and branch lines 15 for feeding combustible gas containing condensable tarry constituents from said main to said consuming appliances, means for preventing

deposition of said constituents in said system comprising a burner communicating with each of said branch lines for producing hot products of combustion, means for mixing said products of combustion with the gas flowing through said lines in amount and at a temperature to compensate for heat losses from said combustible gas during its flow through said distribution system to said appliances, means including a valved conduit for supplying air to the burner, 10 means including a valved conduit for withdrawing a portion of the combustible gas from said system and supplying it to the burner, and means responsive to pressure conditions in said system for automatically closing said gas and air valves 15 when the pressure in said system falls below a predetermined minimum.
